FIG. 1

FIG. 2

FIG. 3

FIG. 1 is a side elevation of a decorative side panel for a dental chair showing my new design;

FIG. 2 is an end elevation thereof; and

FIG. 3 is a perspective view thereof.

The broken lines representing the dental chair is shown for illustrative purposes only.

The characteristic features of my design reside in the V-shaped configuration of the side panel as best illustrated in FIG. 2 on the drawing.

This application is a continuation-in-part of design application Ser. No. D. 25,479, filed Oct. 14, 1970 and now abandoned.

I claim:

The ornamental design for a decorative side panel for dental chair, as shown and described.
